UNITED STATES PATENT OFFICE.

HENRY F. GABEL, OF PITTSBURG, PENNSYLVANIA.

DESIGN FOR A GAS-BURNER.

SPECIFICATION forming part of Design No. 30,668, dated May 2, 1899.

Application filed March 21, 1899. Serial No. 709,985. Term of patent 7 years.

To all whom it may concern:

Be it known that I, HENRY F. GABEL, of Pittsburg, in the county of Allegheny and State of Pennsylvania, have invented a new and original Design for Gas-Burners, of which the following is a full, clear, and exact description, reference being had to the accompanying drawings, forming part of this specification, in which—

- 10 Figure 1 is a side elevation of a gas-burner embodying my new design. Fig. 2 is a cross-section on the line X X of Fig. 1 looking downwardly. Fig. 3 is a view similar to Fig. 2 looking upwardly.
- 15 The leading feature of my design consists in a gas-burner having a globular chamber at its lower end, a hollow stem leading upwardly therefrom and having an enlargement at its

upper end with side slots and a conical shield or top covering the slotted enlargement. 20

In the drawings, 2 represents the body of the burner, having at its lower end a bulb-shaped chamber 3 and in its upper end an enlarged burner-chamber 4, with side slots for the exit of the mixed air and gas, the burner-chamber being covered by a cone-shaped top 5.

I claim—

The design for a gas-burner, substantially as herein shown and described.

In testimony whereof I have hereunto set 30
my hand.

HENRY F. GABEL.
